UNITED STATES PATENT OFFICE.

RICHARD W. GALLAGHER, OF NEW YORK, N. Y., ASSIGNOR, BY MESNE ASSIGNMENTS,
TO CARROLL W. PROCHASKA, OF NEW YORK, N. Y.

CARBURETER.

1,148,485.

Specification of Letters Patent. Patented July 27, 1915.

Application filed August 1, 1913. Serial No. 782,460.

To all whom it may concern:

Be it known that I, RICHARD W. GALLAGHER, a citizen of the United States, residing in the borough of Manhattan of the city of New York, in the State of New York, have invented certain new and useful Improvements in Carbureters, of which the following is a specification, reference being had to the accompanying drawings, which form a part hereof.

This invention relates to carbureters and has for an object to improve generally the construction thereof whereby the efficiency is increased, the entire structure rendered more compact and substantial than hitherto and the cost of manufacture decreased.

More particularly the invention is concerned with improvements in the details of construction of the various parts and their arrangement with respect to each other.

In previous constructions it has been proposed to form the Venturi tube centrally of the float chamber, but it has not been the practice to form in the wall of the Venturi tube, the gasolene passage from the float chamber, an adjustable low speed gasolene control and a traveling high speed gasolene control. In accordance with the present invention the Venturi tube is formed with such a gasolene passage in which is removably disposed a nozzle, the character of which regulates the character of the gasolene spray. The discharge of gasolene from the nozzle may be through independent ducts controlled in turn by adjustable low speed and high speed needle valves respectively. The low speed gasolene duct, which is also formed in the wall of the Venturi tube is so disposed with respect to the gasolene level in the float chamber that the supply of fuel therethrough is induced partially through capillary action.

A further object of the invention is to improve the means for controlling the supply of high speed air and its introduction into the fuel supply so that a more complete and intimate mixture is formed and a more sensitive control of the motor obtained than has been possible in previous constructions. The disposition of the high speed air inlet in the casing is also made with a view to rendering the entire device as compact as is consistent with efficient operation.

The invention is concerned also with other

improvements which will appear more fully as this description proceeds.

The invention will be described more fully with reference to the accompanying drawings in which—

Figure 1 is a view in side elevation of a carbureter embodying the present improvements, parts being broken away to show details of construction. Fig. 2 is a view in section on the plane indicated by the line 2-2 of Fig. 1 and looking in the direction of the arrows. Fig. 3 is a plan view, partly in section, of the carbureter shown in Fig. 1. Fig. 4 is a detail view on an enlarged scale of the fuel passage from the float chamber showing the removable nozzle therein and the low and high speed needle valves in operative position with respect thereto.

The carbureter here shown embodies in the main, parts corresponding to carbureters now known, the casing thereof being formed to provide a float chamber *a* of substantially cylindrical form and having disposed centrally therethrough a Venturi tube *b* in which low speed air and fuel are combined and pass through an outlet *b'* to the motor, as will be understood. In the float chamber is disposed an annular float *c* preferably encircling the Venturi tube *b* and suspended from a forked member *d* fulcrumed between its ends, as at *d'*, and operatively connected at its outer end to an adjustable needle valve *e* which controls the flow of fuel through the passage *f* from any suitable supply to the float chamber. The invention is not concerned with the construction of the float or the needle valve *e* or their connections. However, it is now proposed to inclose partially the stem of the needle valve *e* by a sealed cap *a'* threaded in the upper wall of the casing of the float chamber *a*, and provided with an air vent *a''*.

In the wall of the Venturi tube *b* is formed a passage leading from the interior of the float chamber *a* to a point substantially centrally disposed of the Venturi tube, so that the fuel will be discharged directly in the path of the low speed air supply which passes upward and through the Venturi tube in a manner well known. Within the passage may be threaded removably a nozzle *g* through the bore of which the fuel actually passes. The upper end of the nozzle *g* is preferably tapered, as at *g'*,

to fit snugly within the upper end of the passage first described which is correspondingly tapered. The tapered portion g' of the nozzle g forms between itself and the wall of the passage in which the nozzle is disposed, an annular chamber h into which fuel may pass from the nozzle through a series of apertures g^2 formed in the nozzle adjacent the gas chamber. The upper end of the nozzle g communicates with the interior of the Venturi tube adjacent its throat or restricted section through a duct g^3 having formed therein a valve seat g^4 with which the high speed traveling needle valve i operates in a manner to be pointed out later. The gas chamber h communicates in turn, through a duct b^2 , with a valve controlled passage b^3 which permits the flow of fuel into the interior of the Venturi tube. The duct b^2 and the passage b^3 , above referred to, are controlled by a low speed needle valve k in a manner which will appear presently. It should be noted here that the valve seat g^4 in the nozzle g is disposed at a lower level than the discharge end of the passage b^3 and that the discharge end of the passage b^3 is normally higher than the level of the fuel in the float chamber. The effect of such an arrangement is to insure, through capillary action, a slight discharge of fuel through the passage b^3 aided by the suction of the motor. Thus, when the high speed valve i is seated firmly to close the duct g^3 , capillary action and the suction of the motor will cause a welling over of fuel through the discharge passage b^3 and such a discharge will be sufficient to insure idle running of the motor. From the arrangement above described, it will appear that gasoline or other fuel may flow from the float chamber a through the nozzle g and discharge through the duct g^3 into the Venturi tube, provided, of course, that the high speed traveling needle valve i is raised from its seat. It will be understood that the valve i will, during normal operating conditions, be raised from its seat and assume substantially the position indicated in Fig. 4. When the valve i is seated, however, the fuel may take a different channel and pass through the apertures g^2 into the chamber h from whence it may flow through the duct b^2 and the passage b^3 into the Venturi tube and there combine with a suitable supply of air to form a mixture of proper proportions for idle running of the motor.

It will be evident to those skilled in the art that it will be desirable to provide nozzles g of different characters, that is, nozzles having larger or smaller bores, greater or less tapers, discharge ducts g^3 of varying size and apertures g^2 of varying diameters. By the construction herein employed the nozzles g may be interchanged readily by forming their threaded portions of standard

types. The advantage of control of the gasoline or fuel flow at the point of its discharge into the Venturi tube will be appreciated.

While, as indicated in Fig. 2, the supply of atmospheric air to the lower end of the Venturi tube is obtained as usual, the high speed air supply is controlled in the present carburetor by an improved valve and inlet passage, both constructed and arranged to permit a more compact and efficient disposition than has been obtained in similar devices now known. This high speed air valve and its communicating passage will now be described. Reference to Fig. 1 shows that the casing above the float chamber a is extended at one side to form the vertically disposed high speed air chamber b^4 of substantially cylindrical form which receives a rotatable valve body l having a stem l' operatively connected to the usual manual control as will later appear. The air chamber b^4 has formed in the walls thereof an inlet slot b^5 . The valve body l which controls the opening b^6 may be formed with a segmental wall constituting a control shutter therefor. Since it may be desirable at times to remove the valve member l for purposes of inspection, cleaning, etc., a removable cap b^6 is threaded in the upper wall of the valve chamber b^4 , as appears clearly in Fig. 1. The cap b^6 may be formed with an annular flange b^7 to receive and guide the operating stem l' of the valve l .

From the valve chamber b^4 the air passes to the outlet duct through a tapered or progressively narrowing passage b^8 which is preferably integral with the Venturi tube and with the high speed air chamber b^4 . The cross sectional area of the passage b^8 adjacent its inner end is materially less than its cross sectional area at its point of communication with the air chamber b^4 , with the result that the air is discharged into the fuel in the Venturi tube at a relatively high velocity. In this manner an intimate mixture of the air with the fuel is secured and the use of mechanical or other mixers is obviated.

In the outlet duct b' for the mixture and above the point of introduction of the high speed air into the fuel stream, is mounted the usual butterfly valve m controlled through suitable link connections m' by the operator. In the wall of the outlet passage b' and in juxtaposition to the periphery of the butterfly valve m is threaded a grooved stud n to provide a by-pass for the mixture for idle running of the motor when the butterfly valve is in closed position. The stud n is preferably disposed parallel to the stem of the butterfly valve m and is formed intermediate its ends with a groove n' , so that when the butterfly valve m is in closed position, as indicated in Fig. 1, its periphery lies against

the stud n . By reason of the groove n' , however, a by-pass for the mixture is left between the butterfly valve and the stud. The cross sectional area of this by-pass may be varied readily by rotating the stud n to change the angular relation of the wall of the groove n' with respect to the inner wall of the passage b' . Such an adjustment may be made initially for the particular motor to which the carbureter is attached and, once made, serves for an indefinite time for a proper fuel supply for idle running of the motor.

Another feature of importance in connection with the stud n and its groove n' is the provision in the wall of the passage b^2 of a cup-like chamber, indicated at b^9 , constituting a part of the aperture to receive the stud. Such a chamber b^9 will always be found within the groove n' . By reason of the normal relation of the groove n' to the butterfly valve m , when the latter is in closed position, condensation of the fuel which, as usual, results in a deposit thereof on the butterfly valve, permits a deposit of such condensed fuel in the cup-like chamber b^9 . Such a deposit will serve as a starting charge for the motor and will render unnecessary the priming which is usually resorted to.

Having described the structure of the various operating parts and pointed out their respective functions, it is believed that a recital of their relations each to each together with their operative connections to each other and to the master control, will now be appreciated. The slow speed fuel supply passage b^2 may be controlled, as indicated before, by the needle valve k which may be threaded in the wall of the Venturi tube and which is manually adjusted through a milled head k' and held in set position by a suitable spring or similar device k^2 which co-operates with the head. The high speed fuel duct g^3 , however, is controlled by the traveling needle valve i which may be threaded in the wall of the casing or, as illustrated, in a sleeve b^{10} removably secured in the wall. The traveling needle valve i may also be provided with a milled head i' whereby manual adjustment is facilitated and such initial adjustment may be maintained by a spring clip or similar device i^2 in engagement with the head. On the stem of the valve i may be secured a link o having a longitudinal slot o' in which is loosely disposed an arm p secured adjustably on one end of the protruding stem m^2 of the butterfly valve m . A split ring clamp $\tilde{v}^3$ is fixed with relation to the spring clip i^2 and the link o , on the stem of the valve i and when loosened permits the valve to be rotated in the sleeve b^{10} to adjust its initial position with respect to the valve seat. When the ring $\tilde{v}^3$ is subsequently clamped to the stem of the valve i , the spring i^2 holds the valve in this rela-

tive position. By sliding the arm p along the stem m^2 and the slot o' its radial distance with respect to the needle valve i may be varied and the speed of travel of the latter changed accordingly. As pointed out before, the other end of the stem m^2 of the butterfly valve m also protrudes beyond the casing and has secured thereto the link connection m' with the manual control for the operator. On the last named end of the stem m^2 may be secured adjustably an arm q in operative engagement through a universal connection with one end of an arm r , the other end of which may have a ball and socket or universal engagement with the stem l' of the high speed air inlet valve l . The connections described above permit simultaneous and proportional movement of the butterfly valve, the high speed air inlet valve and the traveling high speed fuel valve i . The several independent adjustments permitted with respect to each of these connections, as indicated in the description of the respective parts, permits the phase of each of the members to be varied with respect to the remaining interconnected members. In this way, by proper initial adjustment, a very fine adjustment of a correct proportion of fuel and air for different speeds of the motor may be obtained.

From the description thus far given the method of operation of the carbureter will be evident. The low speed air supply, pre-heated if desired by the means herein provided, enters the lower end of the Venturi tube and passes upward therethrough. At the throat or restricted portion of the Venturi tube this air unites, when the high speed valve i is seated, with low speed fuel discharged from the passage b^3 , partially by capillary action and partially by induction of the motor. At this time, the high speed air valve l closes completely the inlet slot b^5 and the butterfly valve m may be in its closed position, so that the mixture passing upward to the motor flows thereto through the by-pass n' in the adjustable stud n . When any load is thrown on the motor it will be found desirable to increase the volume of the mixture as well as, perhaps, the proportions thereof. Accordingly, the operator may open partially the butterfly valve m through the link m' . Simultaneously, by reason of the interconnections hereinbefore pointed out, the high speed air inlet valve l will be opened partially, to admit a proportional volume of air through the slot b^5 , and the high speed traveling valve i will be unseated to admit a proportional volume of fuel.

In practice, the carbureter herein disclosed has proved to be highly efficient and this efficiency is attributed largely to the compactness thereof and to the improved arrangement and construction of the oper-

ating parts. While it is recognized that the operating parts may have their functional equivalents in the prior art, it is believed that their improved character, as herein pointed out, together with their novel arrangement result in the advantages herein sought to be obtained.

I claim as my invention:

1. In a carbureter, the combination of a Venturi tube, a float chamber, a single passage from the float chamber to the Venturi tube, independent ducts communicating with the passage and the Venturi tube, and independent high and low speed valves controlling said ducts respectively.
2. In a carbureter, the combination of a Venturi tube, a float chamber, a single passage from the float chamber to the Venturi tube, a high speed traveling valve operatively mounted in the wall of the Venturi tube to control the flow of gasolene from the mouth of the passage, an independent by-pass duct communicating with the passage and with the interior of the Venturi tube, and a low speed valve mounted operatively in the wall of the Venturi tube to control the flow of gasolene through said duct.
3. In a carbureter, the combination of an integral Venturi tube, a float chamber, a single passage in the wall of said tube from the float chamber to the Venturi tube, a tapered nozzle removably secured in said passage, and a valve mounted operatively in the wall of the Venturi tube to control the discharge of gasolene from the mouth of the nozzle.
4. In a carbureter, the combination of a Venturi tube, a float chamber, a passage in the wall of said tube from the float chamber to the interior of the Venturi tube, a

nozzle removably secured in said passage, a chamber formed in the wall of the passage, an aperture in the nozzle to permit the flow of gasolene into said chamber, an independent passage from the chamber to the interior of the Venturi tube, and high and low speed valves to control the discharge of gasolene from the mouth of the nozzle and through the last named passage respectively.

5. In a carbureter, the combination of a Venturi tube, a float chamber, a nozzle removably secured in the wall of the Venturi tube and communicating with the interior of the tube and with the float chamber, a high speed traveling valve operatively mounted in the wall of the tube to control the discharge of gasolene from the mouth of the nozzle, an independent capillary passage from the nozzle to the interior of the Venturi tube, and a slow speed valve operatively mounted in the wall of the tube to control the flow of gasolene through the last named passage.

6. In a carbureter, the combination of a Venturi tube, a float chamber, a passage in the wall of said tube from the float chamber to the interior of the Venturi tube, a chamber formed in the wall of the passage, an independent passage from the chamber to the interior of the Venturi tube, and high and low speed valves to control the discharge of gasolene from the mouth of the first named passage and through the last named passage respectively.

This specification signed and witnessed this 26th July A. D., 1913.

RICHARD W. GALLAGHER.
